UNITED STATES PATENT OFFICE.

LEO MORSE, OF NEW YORK, N. Y.

DESIGN FOR A SIFTER-BOX OR SIMILAR ARTICLE.

51,024.

Specification for Design.

Patented July 10, 1917.

Application filed April 11, 1917. Serial No. 161,359. Term of patent 3½ years.

To all whom it may concern:

Be it known that I, LEO MORSE, a citizen of the United States, and resident of the city of New York, borough of Manhattan, in the county of New York and State of New York, have invented a new, original, and ornamental Design for a Sifter-Box or Similar Article, of which the following is a specification, reference being had to

the accompanying drawing, forming part thereof.

The figure is a front elevation of a sifter box or similar article, showing my new design.

I claim:

The ornamental design for a sifter box or similar article, as shown.

LEO MORSE.
